CASH RECEIVER

John J. Murtaugh, Jr., Flora Park, N. Y., assignor to The Mosler Safe Co., Hamilton, Ohio, a corporation of New York

Application April 2, 1936, Serial No. 72,311

9 Claims. (Cl. 232—1)

This invention relates to a cash receiver adapted to issue a receipt automatically to the depositor each time a deposit is placed in the receiver, and more particularly relates to cash receivers adapted to be used in stores and other places to receive from the employees cash or other valuables for safe keeping or for collection.

In the larger department stores and in other places where the schedule is such that a great number of employees are ready at the same time to make deposits of cash or other valuables for safe keeping or for collection, it has been customary to have a number of receiving clerks to whom these deposits are given and who write out and hand a receipt to the depositing employee. The employment of such receiving clerks entails expense, which is frequently quite large because of the number of receiving clerks that are required to handle a large number of deposits in quick succession and without entailing objectionable delay and waiting. This practice also obtains in other business establishments in which a large number of employees are frequently ready at approximately the same time to deposit collections or other matter.

A principal object of my invention is to provide a receiver in which a deposit may be made and a receipt therefor secured quickly and conveniently, and which eliminates the necessity of having clerks to receive and receipt for deposits, and which eliminates the attendant expense and labor.

Another object of this invention is to provide a receiver of the character described and one which is equipped with means whereby each receipt is clearly and definitely allocated to the deposit for which the receipt issued, and for safeguarding against the failure of a receipt being issued for any separate deposit.

In view of the fact that frequently a great number of depositors must be served in quick order to avoid serious confusion, delay, and annoyance, it is important that the receiver be maintained continuously in operating condition, and, accordingly, another object of my invention is to provide a receiver of the character described, and one in which the paper roll or other receipt supply of the receipt issuing mechanism may be renewed quickly and easily and entailing only a very brief suspension of the use of the receiver, and a further object of this invention is to provide a receiver of the character described and in which the receipt issuing mechanism may be removed from and placed in the receiver quickly

and easily so that, in the event it is desired to clean or adjust or repair the mechanism, it may be quickly and conveniently removed from the receiver for this purpose, or may be replaced quickly and conveniently by another unit which is in order, whereby only a very brief suspension of operation of the receiver is necessitated when such attention to the mechanism becomes necessary or is desired.

A further object of this invention is to provide a receiver of the character described which is simple, sturdy, and durable in construction, one which is simple, easy, and convenient to use, and one which effectively takes care of the deposits presented thereto.

Other objects of this invention will be in part obvious and in part pointed out hereinafter.

In order that a clearer understanding of this invention may be had, attention is hereby directed to the accompanying drawings, forming a part of this application, and illustrating certain possible embodiments of this invention and in which:

Fig. 1 is a perspective view of a receiver embodying this invention;

Fig. 2 is a vertical sectional view of the receiver and is taken on the line 2—2 of Fig. 3;

Fig. 3 is another sectional view of the receiver and is taken on the line 3—3 of Fig. 2; and

Fig. 4 is a wiring diagram of the electrical circuits of the receiver.

Similar reference characters refer to similar parts throughout the several views of the drawings.

Referring to the drawings, the receiver includes a chest or other suitable receptacle 10 for storing deposits presented to the receiver, the chest being provided with a suitable door 11. On the top of this chest is mounted a box 12 having side walls 13 and 14, front wall 15, rear wall 16, which is higher than the front wall, and has an interior vertical partition 17 extending between the side walls whereby there is established between rear wall 16 and partition 17 a chute space 18 open at the bottom and there registering with a corresponding opening 19 provided in the top 20 of chest 10. There is thus also established between the front wall 15 of box 12 and partition 17 a compartment 21 adapted to house receipt issuing mechanism and other mechanical and electrical elements of the receiver. Compartment 21 is closed at the top by a plate 22 which extends from the wall 15 to the partition 17.

At the top of chute 18 there is a top plate 23 and immediately under this plate is positioned a

drawer 24, having rollers 25 resting on cleats or tracks 26 secured to the side walls 13 and 14 of box 12 and whereby the drawer is supported so that it may be pulled out from under the top plate 5 23 and over the top plate 22 of compartment 21 to allow a deposit to be placed therein. Spring means, which may take the form of spring tensioned reels 27 of tapes 28, having the reels rotatably mounted on the opposite side walls 13 and 14 10 and having the ends of the tapes 28 attached to pins 29 or the like secured to the sides of the drawer, may be provided to automatically quickly close the drawer after it has been opened and then released. Drawer 24 has a bottom 30 which 15 at its forward edge is hinged to the front wall 31 as by means of hinges 32. When the drawer is pulled open, the bottom 30 engages the top of partition 17 and is raised and held up thereby, and, when the drawer is closed, bottom 30 drops 20 and anything that may have been placed in the drawer drops through chute 18 and the aperture 19 in the top of chest 10 and comes to rest in the chest. Within compartment 21 is housed a supporting standard or frame comprising a bottom 25 plate 33 on which is formed or mounted a vertical plate 34, and on this pedestal or frame is carried the receipt issuing mechanism and certain 30 of the controls therefor. One of the side walls, such as 13, is provided with a suitable opening 35 through which this pedestal or frame, with all its parts intact thereon, may be removed easily and conveniently. A door 35, hinged as at 36 to the wall 13, is provided for closing this opening. The 40 receipt issuing mechanism may be any one of a number that are available on the market, and therefore such mechanism is not shown in great detail in the drawings. There is shown, however, the driving motor 37 connected by suitable gearing 38 to the cam-ratchet wheel 39, which turns coincident with the operation of the receipt issuing 45 mechanism. A detent 40, pivoted on a pin 41 carried on frame plate 34, normally engages the shoulder 42 of cam 39 to prevent rotation of this cam and thus prevents operation of the receipt issuing mechanism.

Means are provided whereby a deposit dropping through chute 18 starts the receipt issuing mechanism in operation to issue a single receipt and then to stop operating, and means are also provided for preventing the drawer 24 from being opened during the time the receipt issuing mechanism is operating. To these ends a baffle 43, 50 rocking on a bracket 44 secured to partition 17, extends into chute 18 in position to be deflected downward by a deposit dropping through the chute, and this baffle has a heel portion 45 on the opposite side of partition 17 which normally engages a spring contact 46 and holds it separated from a mating contact 47, contact 46 coming 55 against contact 47 when the baffle is rocked by a passing deposit.

Associated with detent 40, and mounted on frame plate 34, is a solenoid 48 which, when energized, will raise detent 40 and release cam 39 to rotate. When raised, detent 40 also displaces a spring contact 49 so that it will contact a terminal 50, and detent 40, when raised, will also move a resilient contact 51 against another contact 52. The contacts 49, 50, 51, and 52 are also mounted 60 on the frame plate 34.

Slidably mounted in guides 53, secured to the partition 17 adjacent to its upper edge, is a bolt 54 having a lug 55 engaged from below by one end of a lever 56 pivoted on a bracket 57 secured to the top wall 22. Lever 56 has a heel portion 58

which engages, and normally holds, resilient contact 59 closed against another contact 60, contacts 59 and 60 being carried on a bracket 61 which is secured to the top 22. Associated with lever 56 is a solenoid 62 carried by bracket 57 and adapted, when energized, to rock lever 56 to raise the upper end of bolt 54 into a keeper slot 63 formed in an offset portion 31' on the lower edge of the front 31 of drawer 24. While solenoid 62 is energized, the door will be locked against being 10 opened, but will automatically become unlocked when solenoid 62 becomes de-energized. At the same time that lever 56 moves bolt 54 upwardly, its heel portion 58 releases resilient contact 59 so as to break the contact with contact 60. 15

Fig. 4 shows the wiring diagram of the circuits of the receiver, and the operation will now be explained in connection therewith. The receiver is provided with a suitable pair of terminals 65 and 66 with which power lines from an outside 20 source of current supply may be connected. A conductor 67 connects one of these terminals to one side of the motor 37, from which a conductor 68 leads to contact 52, and the opposite contact 51 is connected by conductor 69 to the other terminal 66 so that the power circuit through the motor is closed whenever the switch comprising terminals 51 and 52 is closed, and this circuit is broken when this switch is open. Consequently, when solenoid 48 is energized, thus raising detent 30 40, not only is the cam wheel 39 released, but the switch comprising terminals 51 and 52 is closed and the motor 37 starts rotating. Cam 39 then holds switches 49, 50 and 51, 52 closed during a full turn of the cam. 35

Contacts 46 and 47, and contacts 59 and 60 are connected in series in a circuit which is closed whenever the baffle 43 is deflected by a deposit. As shown, a conductor 70 connects the lead 67 with contact 60 and from the opposite contact 59 40 a conductor 71 leads to contact 47, conductor 72 leading from contact 46 to solenoid 48, from which conductor 73 connects with the opposite power lead 69. 45

The switch comprising contacts 49 and 50 is in 50 series with a solenoid 62 in a circuit which includes a conductor 74 leading from power line 67 to the solenoid, conductor 75 leading from the solenoid to contact 49, and conductor 76 leading from contact 50 to the opposite power line 69. 55 As aforesaid, when detent 40 is raised by reason of solenoid 48 being energized in consequence of the closing of the switch comprising the terminals 46 and 47 by a deposit passing through the chute 18, the switch comprising the terminals 49 and 50 60 is closed by the detent, completing the circuit through relay 62, which thereupon rocks the locking lever 56 to lock the drawer against being opened and, at the same time, opens the switch comprising the contacts 59 and 60, thus establishing a break in the circuit which includes solenoid 48. The reason for breaking this latter circuit at the terminals 59 and 60 is because the baffle 43 might have a tendency to continue rocking after it has been deflected by a deposit, and cause 65 contacts 46 and 47 to come together and separate, and the purpose of breaking this circuit at contacts 59 and 60 is to prevent any chattering and sparking that might otherwise result from such repeated closing and opening of the contacts 46 70 and 47.

It will be noted that the actuation, operation, and safeguarding of the operation is entirely automatic from the time a person has placed a deposit in the drawer and has closed the drawer, 75

until the receipt has been issued and the operation of the receipt issuing mechanism has ceased.

Preferably all conductors which are connected with any of the parts mounted on the supporting frame 33, 34 are provided with suitable plugs removably engageable in sockets mounted in any suitable location in compartment 21 and to which other conductors of the circuit are connected, so that, when it is desired to remove the receipt issuing mechanism, it is only necessary to open the door 35, disengage these plugs from the sockets, and remove the frame 33, 34 and all the parts thereon from compartment 21 through the aperture in the side wall 13. This removed unit or another unit may be placed in the compartment with similar ease and convenience, since all that is necessary is to place the unit in the compartment and engage the plugs in the proper sockets to complete the circuits.

The roll 80 of paper for the receipts may be rotatably and removably carried on a spindle 81 mounted on a bracket 82 secured to the partition 17 so that the roll may be renewed or removed easily and conveniently through the aperture in the side wall 13 of box 12. The front wall 15 is provided with a suitable aperture 83 through which the receipt issuing mechanism discharges the receipts and, if desired, a cup 84 may be provided in front of this aperture to catch the receipts so that they can be picked up easily and quickly by the depositor.

As a further protection, a closure plate 90 may be mounted against the under surface of the top plate 20 of chest 10 to slide on track members 91, secured to this top plate, into position closing the aperture 19. This closure 90 may be held away from this opening by a finger latch 92 which is pivotally mounted on a bracket 93 positioned within compartment 21, and a coil spring 94 may be extended between a hook 95 on the chest and an eye 96 secured to closure 90, adjacent to its front edge, to pull closure 90 across opening 19 whenever the closure is released from latch 92. Latch 92 is preferably provided with finger piece 93 whereby the latch may be retracted to release closure 90 to close the opening 19. Closure 90 may be returned to original position by opening the door 11, reaching into chest 10, and retracting the closure until it is automatically engaged by latch 92.

To make a deposit, the depositor merely pulls the drawer open, places the deposit therein, and lets go of the drawer, and in a very few seconds time the receipt for that deposit will be delivered into the cup 84, from which the depositor can quickly and easily remove it. Meanwhile, until the receipt has issued, the next depositor can not open the drawer to make a deposit, and thus each issued receipt is definitely allocated to the deposit for which it has issued, and deposits can not be made in such quick succession as might result in the issuance of only a single receipt for a plurality of deposits. In view of the very short time that is required to make a deposit and to secure the receipt therefor, the receiver is adapted to handle efficiently separate deposits in very rapid succession, and a line of depositors may be taken care of in very rapid order.

By arranging the drawer so that it slides over the top of the compartment which houses the receipt issuing mechanism, and arranging for the issuance of the receipts at the front of this compartment, there is secured an arrangement such that the depositors may make the deposits and secure the receipts very conveniently and

quickly, thus tending to conserve time. Locating the receipt issuing and control mechanism within the forward compartment disposed on top of the receiving chest not only secures the issuance of the receipt at the convenient location referred to, but also locates the paper roll for the receipts and the mechanism in a location in which it is readily and conveniently accessible for renewal of the paper or for adjustment or replacement of the mechanism. As explained hereinbefore, the paper roll for the receipts may be renewed very quickly, and also the receipt issuing mechanism may be removed and replaced easily and quickly through the aperture provided for this purpose in the side wall of the box. This structural arrangement also leaves the interior of the chest 10 substantially free, and makes the entire interior of the chest available to receive the deposits and prevents the deposits from coming into contact with the receipt issuing mechanism, other than the baffle 43, thus avoiding any danger of the mechanism being damaged or put out of adjustment thereby.

From the above, it will be readily apparent that the receiver embodying this invention may be used effectively in place of clerks employed for the purpose of receiving deposits and issuing receipts therefor, and that a receiver embodying this invention is adapted to take care of deposits in very rapid succession, as well as in slow order.

As many changes could be made in the above construction, and as many apparently widely different embodiments of this invention could be made without departing from the scope thereof, it is understood that all matter contained in the above description or shown in the accompanying drawings be interpreted as illustrative and not in a limiting sense.

What I claim is:

1. A receiver of the character described, including, a structure having a storage compartment, a front compartment above the storage compartment, and adapted to house receipt issuing mechanism, and a chute compartment behind said front compartment, means including a member at the upper part of the chute compartment, and movable above said front compartment, for introducing articles into the chute compartment to pass therethrough into the storage compartment, and means for locking said member against movement operable in response to operation of said receipt-issuing mechanism.

2. In a receipt issuing, article receiver of the character described, and having an opening for the introduction of articles, a closure for said opening, a latch engageable with the closure to hold the closure closed, receipt issuing mechanism and an operating circuit for said mechanism, of a locking circuit, means in and responsive to the locking circuit and engaging said latch to place and hold said latch in latching engagement with said closure when and while the locking circuit is closed, and means in the locking circuit and associated with the receipt issuing mechanism to maintain the locking circuit closed whenever the receipt issuing mechanism is operating.

3. In a receipt issuing, article receiver of the character described, and having an opening for the introduction of articles, a closure for said opening, a latch engageable with the closure to hold the closure closed, receipt issuing mechanism and an operating circuit for said mechanism, of a locking circuit, means in and responsive to the locking circuit and engaging said

- latch to place and hold said latch in latching engagement with said closure when and while the locking circuit is closed, means in the locking circuit and associated with the receipt issuing mechanism to maintain the locking circuit closed whenever the receipt issuing mechanism is operating, a control circuit controlling the operation of the operating circuit, means in the control and operating circuits and responsive to the control circuit to close the operating circuit upon the closing of the control circuit, and means in the control circuit and adapted to be actuated by an article introduced into said opening to close the control circuit.
15. 4. In a receipt issuing, article receiver of the character described, and having an opening for the introduction of articles, a closure for said opening, a latch engageable with the closure to hold the closure closed, receipt issuing mechanism and an operating circuit for said mechanism of a locking circuit, means in and responsive to the locking circuit and engaging said latch to place and hold said latch in latching engagement with said closure when and while the locking circuit is closed, means in the locking circuit and associated with the receipt issuing mechanism to maintain the locking circuit closed whenever the receipt issuing mechanism is operating, a control circuit controlling the operation of the operating circuit, means in the control and operating circuits and responsive to the control circuit to close the operating circuit upon the closing of the control circuit, and means in the control circuit and adapted to be actuated by an article introduced into said opening to close the control circuit, and means in said locking and control circuits to open the control circuit when the locking circuit is closed.
30. 5. In a device for receiving articles and issuing a receipt therefor, a chute through which articles are passed, a closure for said chute, a member actuated by an article passing through said chute, mechanism for issuing a receipt for the article, and means actuated by said member and controlling said receipt-issuing mechanism and said closure for preventing opening of said closure during operation of said mechanism.
45. 6. In a device for receiving articles and issuing a receipt therefor, a chute through which articles are passed, a closure for said chute, a member actuated by an article passing through said chute, mechanism actuated by said member for issuing a receipt for the article and a bolt movable in response to operation of said mechanism to prevent opening of said closure until a receipt has been issued.

7. A receiver of the character described, including, a structure having a storage compartment, a chute extending upward from said storage compartment, a receipt-issuing mechanism positioned adjacent said chute, a drawer, mounted on the structure, to be closed into the upper portion of the chute compartment, and to be moved therefrom to a deposit-receiving position, said drawer having means whereby, when said drawer is closed into the chute compartment, the contents of the drawer are dumped into the chute compartment to pass therethrough into the storage compartment, means operable by an object passing through said chute to initiate operation of said receipt-issuing mechanism, and means for locking said drawer in its closed position during operation of said receipt-issuing mechanism.

8. A receiver of the character described, including, a structure having a storage compartment, a drawer-receiving compartment disposed in elevated position with respect to said storage compartment, means establishing communication between said compartments, a receipt-issuing mechanism associated with said structure, a drawer mounted on said structure so as to move into and out of said drawer-receiving compartment, means for urging said drawer to closed position, means for automatically dumping the contents of said drawer into the storage compartment when the drawer is brought to closed position, means operable by an object passing from said drawer to said storage compartment to initiate operation of said receipt-issuing mechanism, and means for locking said drawer in its closed position during operation of said receipt-issuing mechanism.

9. A receiver of the character described, including, a structure defining a storage compartment and a drawer-receiving compartment, a receipt-issuing mechanism associated with said structure, a drawer mounted on said structure so as to move into and out of said drawer-receiving compartment, means establishing communication between said compartments, means associated with said drawer whereby transfer of the contents of said drawer to said storage compartment is effected automatically when the drawer is brought to closed position, means operable by an object passing from said drawer to said storage compartment to initiate operation of said receipt-issuing mechanism, and means controlled by said receipt-issuing mechanism for locking said drawer in its closed position during operation of said receipt-issuing mechanism.

JOHN J. MURTAUGH, JR.
